UNITED STATES PATENT OFFICE.

WILLIAM S. MATHER, OF NEWARK, NEW JERSEY.

SMELTER'S CRUCIBLE-SHAKER.

SPECIFICATION forming part of Letters Patent No. 650,648, dated May 29, 1900.

Application filed January 20, 1900. Serial No. 2,100. (No model.)

To all whom it may concern:

Be it known that I, WILLIAM S. MATHER, a citizen of the United States, residing at Newark, in the county of Essex and State of New

5 Jersey, have invented certain new and useful Improvements in Smelters' Crucible-Shakers; and I do hereby declare the following to be a full, clear, and exact description of the invention, such as will enable others skilled in 10 the art to which it appertains to make and use the same, reference being had to the accompanying drawings, and to the letters of reference marked thereon, which form a part of this specification.

15 The objects of this invention are to provide a shaking device for properly settling the contents of a hot crucible in the process of recharging crucibles according to my improved method of smelting crucible-steel as 20 set forth in my contemporaneous application Serial No. 2,102, to thus enable the crucibles to be properly filled even when too hot to be handled or even closely approached by the hand, and to secure other advantages and re- 25 sults, some of which may be referred to hereinafter in connection with the description of the working parts.

The invention consists in the improved smelter's crucible-shaker herein described 30 and in the arrangements and combinations of parts of the same, all substantially as will be hereinafter set forth, and finally embraced in the clauses of the claim.

Referring to the accompanying drawings, 35 in which like letters of reference indicate corresponding parts in each of the several views, Figure 1 is a side elevation of my shaker in its preferred form as applied to a crucible, and Fig. 2 is a rear view of the same. Fig. 40 3 is a vertical central section of a portion of the shaking-lever; and Fig. 4 is a plan view of the base-plate, the crucible and shaking-lever being shown in outline. Fig. 5 illustrates a modified form sometimes preferred. Fig. 45 6 shows in side elevation a construction in which the base-plate is dispensed with and two levers employed; and Fig. 7 is a section of the same on line x, Fig. 6. Fig. 8 shows a modification of construction, and Fig. 9 is 50 a plan view of the lever in said modification of construction.

In said drawings, *a* indicates a black-lead

crucible or melting-pot, such as is commonly used in smelting crucible-steel, said crucible holding about one hundred pounds, more or less, of metal.

While the metal, which is cut into small pieces to charge the crucible, is being poured into said crucible it is necessary to shake the crucible from side to side—in order to compactly settle the contents and obtain the maximum capacity of the crucible. In the old method of filling the crucible cold this shaking was readily done by taking hold of the pot with the hands; but in my improved 65 method of recharging, above referred to, it becomes necessary to shake the crucible while it is at a cherry-red heat or far too hot to be closely approached, and for this purpose I employ the mechanical shaker forming the subject of this application.

In the preferred form of construction, as shown in Figs. 1 to 4, inclusive, *b* indicates a base plate or stand upon which the crucible *a* is stood, upright pins or blocks *b'* projecting from the said plate around the bottom of the crucible to prevent said crucible from slipping or "walking" about during the shaking operations. Obviously a raised flange, a recess, or any other equivalent means of 80 holding the bottom of the crucible may be used equally well. At one side of said base-plate is a central extension *c*, bent upward, so that its end lies in a vertical position, the said end being rolled or returned upon itself, 85 as at *c'*, to form a transverse eye or bearing for a horizontal pin *d*. The said extension *c* is slotted from its point of leaving the plate *a* to its extreme end in line with a diameter of the circle inclosed by the pins *b'*, and the 90 said pivotal pin *d* extends transversely across said slot *d'*. The said pivotal pin *d* serves to receive the lower forked end *f'* of a shaking-lever *f*, which in the preferred construction of my invention extends upward substantially parallel to the crucible *a* in general direction and to such a height beyond as to be conveniently grasped by a workman without stooping, being shaped for that purpose into a handle *f''* at the upper end. At a point 100 slightly below the top of the crucible *a* when the lever is in operative position said lever carries a horizontally-disposed ring *g*, riveted or otherwise firmly secured at an outer point

of its periphery to the side of said lever next to the crucible. The ring *g* is thus adapted to surround the crucible when the lever is in operative position, said ring being made of proper size for this purpose. In operation, therefore, the still glowing but empty crucible is set upon the base-plate *b* and the shaking-lever *f*, which was removed to allow the last-filled crucible to be taken away, is then replaced, with the ring *g* coming down over the top of the crucible and the lower forked end *f'* of the lever straddling the pin *d*. With the parts in this position one workman pours a charge of cold metal into the crucible by means of my improved pan, which forms the subject of a contemporaneous application, while a second man operates the shaking-lever by swinging it back and forth upon the pin *d* as a fulcrum, and thus violently agitates the crucible to settle its contents compactly together.

The ring *g* is not necessarily made a complete circle, but may be in the segmental form *h*, (shown in Figs. 8 and 9,) if desired, where the arms *h'* *h''* bend sufficiently to hold the crucible from escaping; and, again, I may sometimes place a complete ring *g'* close to the top of the crucible and widen it sufficiently, so that its upper edge projects above the top of the crucible, as shown in Fig. 5, the object of this construction being to prevent any of the contents of a full or nearly full crucible being jolted out as the crucible is shaken, and thus to enable the crucible to be filled full.

In Figs. 6 and 7 I have shown a modified construction in which two levers *i i* are employed, said levers being arranged at diametrically-opposite points of the ring *g*, and said ring having pivotal pins *j* passing loosely through said levers instead of being riveted thereto, as in the previously-described construction. I also prefer to form said pins *j* oval in cross-section and have them lie in similarly-shaped but somewhat larger perforations in the levers. This permits enough looseness for the shaking operations and prevents the ring *g* from swinging into a vertical position, so that it will not slip over the top of the crucible when the shaking-levers are applied. In Figs. 6 and 7, also, I have shown the base-plate as dispensed with and the lower ends of the levers *i* reduced to the form of pins *i' i'*, which enter sockets or holes *k k* in the floor, said sockets being of considerably larger diameter than the pins *i' i'* and permitting the levers to work loosely to shake the crucible.

In Fig. 8 I have shown an extension *l* of the base-plate reaching upward to nearly the top of the crucible and slotted or forked at its top, as at *l'*. A lever *m* in this construction projects from the ring *h* in the same plane therewith, said lever in operative position lying horizontally in the slot *l*.

Various other modifications and variations may be made in the detail construction of

my shaker within the scope of the claims without departing from the spirit and scope of the invention, and I do not wish to be understood as limiting myself by any of the positive descriptive terms employed except as the state of the art may require.

Having thus described the invention, what I claim as new is—

1. In a smelter's crucible-shaker, the combination with a supporting-surface upon which the crucible may stand, of a shaking-lever fulcrumed upon said supporting-surface and having means for grasping said crucible near its top, substantially as set forth. 75

2. The improved crucible-shaker, herein described, comprising a support for the crucible having a receptacle for the lower end of said crucible in which the said crucible is seated and prevented from slipping under the shaking operation, and means for grasping the crucible and shaking the same, substantially as set forth. 80

3. In a smelter's crucible-shaker, the combination with a supporting-surface upon which the crucible may stand, of a lever fulcrumed upon said supporting-surface, and a ring connected to said lever and adapted to surround the top of the crucible, substantially as set forth. 85

4. A smelter's crucible-shaker, comprising a base-plate upon which the crucible stands, means for holding the crucible against sliding on said plate and a lever fulcrumed upon said plate and having means for grasping the crucible near its top, substantially as set forth. 90

5. The improved crucible-shaker herein described, comprising a support having a receptacle for the bottom of the pot or crucible, means for grasping the crucible and means extending away from the grasping means whereby said grasping means and the pot are reciprocally shaken to effect a settling of the scrap within said crucible, substantially as set forth. 95

6. A smelter's crucible-shaker, comprising a supporting-plate adapted to receive the bottom of the crucible, means preventing lateral displacement of the crucible, a lever having a fulcrum upon said plate, and a ring connected to said lever and adapted to surround the top of the crucible, substantially as set forth. 100

7. In a smelter's crucible-shaker, the combination of a base-plate receiving the bottom of the crucible, means preventing the crucible from slipping on the base-plate, said plate having an upward extension at one side, and a lever removably fulcrumed upon said upward extension of the base-plate and having means for engaging the top of the crucible, substantially as set forth. 105

8. In a smelter's crucible-shaker, the combination of a base-plate providing a seat for the crucible, a series of projections upon said base-plate surrounding the crucible, a lever removably fulcrumed at its lower end upon said base-plate and extending upward substan- 110

tially parallel to the length of the crucible, and a band of metal fastened to said lever and lying in a plane perpendicular thereto and being bent to grasp the crucible, substantially as set forth.

9. In a smelter's crucible-shaker, the combination of a base-plate upon which the crucible is set, a circular row of pins projecting from the base-plate around said crucible, an upward extension at one side of the base-plate slotted and provided with a transverse pin, an upright lever forked at its lower end to

straddle said pin, and a ring secured to said lever and slipping over the top of the crucible when the lever is seated upon its fulcrumal pin, substantially as set forth. 15

In testimony that I claim the foregoing I have hereunto set my hand this 29th day of December, 1899.

WILLIAM S. MATHER.
